UNITED STATES PATENT OFFICE

GEORGE ALEXANDER DUNAGIN, OF ATLANTA, GEORGIA

FOLDING MACHINE

Application filed July 18, 1930. Serial No. 463,846.

This invention relates to a device for applying adhesive to letter sheets during the folding of the latter to form envelopes of the sheets, the envelopes being sealed so that the 5 contents of the letters cannot be read without breaking the seal. It has for its object the provision of means for applying the adhesive during the folding operation so that the reading matter will not be obscured and so that 10 the breaking of the seal will not injure the paper to confuse the contents of the letter. The means employed for carrying out the invention are described in detail hereinafter, 15 pointed out in the appended claims, and illustrated by the accompanying drawings.

In the accompanying drawings, in which similar reference characters designate corresponding parts,

Figure 1 shows an elevation of the device 20 for applying the adhesive, with a diagrammatic arrangement of parts of the folding mechanism of the patent to Nind and Julyan, of December 25, 1906, No. 839,313; only so much of the patented device being shown as 25 to illustrate the operation of the adhesive applying device.

Figure 2 is a detail view, showing the tucking blade and the nipples mounted thereon.

Figure 3 is an enlarged detail view, showing 30 the means for mounting a nipple on the tucking-blade.

Figure 4 is a detail perspective view, showing the adhesive reservoir and its mounting.

Figure 5 is a similar view, broken away in 35 part, of a partly folded sheet.

Figure 6 is a detail sectional view, showing 40 the mounting of a nipple on the tucking-blade.

Figure 7 is a detail perspective view of the 45 same.

Figure 8 is a detail view, showing ends of 50 the rolls for making the final fold.

The device is designed to be mounted on 55 folding machines that are in common use. Such a machine is disclosed in Patent No. 839,313, of December 25, 1906, to F. G. Nind and F. Julyan. This patent discloses a machine particularly adapted for folding letter sheets for mailing purposes. One of the 60 elements of the device of the patent is the tuck-

ing blade 94, shown in Figs. 6 and 7 of the patent. The function of this blade is to tuck the previously folded sheet between the rolls 103 and 104 to effect the final fold in the sheet. The machine of the patent can be adjusted to 55 fold a sheet to the form shown in Fig. 5 of the present application. As shown, the sheet is so folded that the outer ply *a* projects at its free edge as at *b* beyond the free edge of the adjacent inner ply *c*. In the completed 60 folded form of the sheet, the three plies *a*, *d* and *e* are coextensive, while the ply *c* is of less width. The purpose of the instant invention is to apply to the inner face of the ply *e*, at the outer corners thereof, as at *f*, slight 65 daubs of adhesive so that when the final fold is completed the corners of the ply *e* will be pasted to the corners of the ply *a* clear of the 70 ply *c*. When so pasted, the plies will be sealed together so that the reading matter on the inner side of the sheet cannot be read without breaking the seals. In this way, the sheet forms the envelope, which can be addressed 75 for mailing in the usual manner. As but little paste is used for the daubs, the seals can be readily broken by the recipient of the letter without injuring the paper to affect the reading matter.

In the instant invention, the means for 80 supplying the paste includes a tubular reservoir 1 mounted in a support comprising the base plate 2 and a top plate 3, supported by the brace rods 4 connecting the corners of the two plates. The support is in the shape of the frustum of a pyramid to provide 85 stability. In the top plate 3 is a central vertical opening in which slides the tubular reservoir 1 with a tight fit. By vertically adjusting the reservoir in the support the elevation of the liquid therein can be 90 regulated. The bottom of the reservoir is closed by the stopper 5 fixed therein and the top is provided with the removable stopper 6 so that the adhesive can be poured into the reservoir. Communicating with the interior 95 of the reservoir and leading through the bottom thereof is the pipe 7, provided with the controlling valve 8. Connected with the outer end of the pipe is the flexible tubing 9, branched at its outer end. At the extremity 100

of each branch of the tubing is the nipple 10. Extending through the bottom of the reservoir and communicating with the upper part thereof is the air-inlet tube 11, provided at 5 its outer end with the valve 12 to regulate the admission of air into the reservoir as the adhesive is withdrawn.

The tucking-blade 94 of the present invention corresponds to the tucking-blade 94 of 10 the patent, supra, and in the folding operation its function is the same. The structure of the blade is modified somewhat to coact with the device for applying the adhesive.

In the opposite ends of the blade 94 are the 15 vertical slots 13 extending upward through the blade. On the back of the blade and over each slot 13 therein extends the guide 14 having in its rear side a slot 15 coinciding with the slot 13. In each guide is slidable

20 a block 16 of elastic material, such as a rubber composition, compressed therein. The block can be adjusted along the guide and is frictionally held in its adjustments. Extending through each block 16 is one of the 25 nipples 10 with its discharge opening projecting through the adjacent vertical slot 13, slightly in advance of the blade 94. The rear end of the nipple extends through the slot 15 in the adjacent guide and is connected

30 with one of the branches of the flexible tubing 9, leading from the adhesive reservoir. The nipples have a tight fit in their respective blocks 16 and can be adjusted therein to project more or less from the face of the 35 tucking-blade to meet different requirements; also, the nipples can be entirely withdrawn from the blocks should it be desirable to operate the machine without the application of the adhesive.

40 In the operation of the device, the adhesive reservoir with its mounting is supported adjacent to the folding machine, the reservoir being elevated above the nipples 10 mounted in the tucking-blade 94 so that the 45 adhesive can flow by gravity through the connection between the reservoir and the nipples. The mechanism of the folding machine is adjusted so that the first fold in a letter sheet will form plies of unequal length

50 to provide the marginal part *b* in the ply *a*—*d*. After the first fold is formed by the rolls 47 and 54 (of the patent), the folded sheet is carried by the tapes 74 and the co-operating guides 113 to a position between the 55 tucking-blade 94 and the coacting rolls 103—104. In this position, the creased edge of the folded sheet rests on the pins 117 and with the ply *a*—*d* abutting the rolls 103—104. So positioned, the lower corners of the ply 60 *c*—*e* are directly opposite to the nipples 10 carried by the tucking blade. As the blade oscillates to tuck the sheet between the rolls 103—104 for the final fold, the nipples are forced lightly against the lower corners of the 65 ply *c*—*e*, as at *f*, and a daub of the ad-

hesive is applied. The oscillation of the blade in the tucking operation is very quick and there is only a momentary contact of the nipples with the paper and but slight daubs of the adhesive are applied. After 70 the tucking operation of the blade, the rolls 103—104 complete the final fold of the sheet. As the folded sheet passes between these rolls, the corners of the ply *e* are pressed into contact with the corners of the marginal 75 part *b* of the ply *a* so that the daubs of adhesive at *f* seal together the two plies *a* and *d*. As the adhesive is applied to the ply *e* in close proximity to the crease between this 80 ply and the ply *d*, the latter is practically sealed to the ply *a*.

When the blade 94 tucks the assembled plies between the rolls 103—104, the lower part of the plies is moved upward to accommodate the tucking movement. Advantage 85 is taken of this upward movement of the lower part of the plies to provide elongated daubs of the adhesive along the inner edges of the ply to seal the ends of the envelope.

To accomplish this purpose, the nipples 10 90 are adjusted to the upper parts of the guides 14, so that a considerable part of the ply *e* extends below the nipples. By adjusting the

nipples longitudinally in the blocks 16, their projection toward the folded sheet can be 95 regulated. When the ply is moved upward in the tucking operation, its inner ends are wiped across the nipples so that narrow streaks of adhesive are applied to the inner 100 ends of the ply parallel to its edges. When the folded sheet, so prepared, passes between the rolls 103—104, the inner ends of the plies *c* and *e*, together with the corners of the margin *b* are pressed together and the entire 105 ends of the envelope are sealed together.

For some purposes, the ends of the ply *c* may be cut away, as indicated by the dotted lines *h*, so that the ends of the ply *e* will be sealed directly to the ply *a*. In this way, should either method of sealing be employed, the 110 letter sheet is formed into a sealed envelope, ready for mailing, and which can be easily opened by the recipient without damaging the paper to confuse the reading matter.

In applying pressure to the plies, the rolls 115 103—104 do not act directly on those parts of the plies to which the adhesive has been applied. In the ends of these rolls are annular grooves, as at 17 Fig. 8, which register with each other and track the travel of the daubs *f*, applied in spots or elongated streaks, so that there will be no direct application of pressure by the rolls to squeeze the adhesive from between the plies to smear the rolls or to cause the stacked letters to adhere to each 120 other. During the folding of the sheet and as its lower part moves upward, the daubs *f* thereon travel opposite the slots 13 and cannot contact with the tucking-blade to foul the same.

The supply of the adhesive from the reservoir 1 can be readily controlled to meet the requirements. When the machine is set in operation, the cocks 8 and 12 are opened, the former to permit the flow of adhesive from the reservoir through the flexible tubing 9 to the nipples 10 and the cock 12 to admit air through the pipe 11 to replace the adhesive as it flows from the reservoir. Also, by vertically adjusting the reservoir in the top plate 3 of the support, the liquid can be maintained approximately at a constant head to insure a uniform flow of the adhesive as its level lowers in the reservoir. The fluidity of the adhesive depends on its composition, temperature and other conditions; by means of the several adjustable controls, the device can be regulated to accommodate the fluidity of the adhesive so that the required flow at the nipples can be secured to provide the necessary daubs. By adjusting the blocks 16 in their guides, the nipples can be positioned to accommodate sheets of different length and of different folds. While two nipples have been shown, it is apparent that additional ones can be employed by providing additional mountings on the tucking-blade and providing additional branches to the flexible tubing.

30 What I claim is:—

1. In a folding machine, the combination of a movable element operative to engage a sheet preliminary to a subsequent folding of the sheet, with a source of liquid adhesive, 35 and a nipple communicating with the source of adhesive and mounted in the movable element to apply a daub of the adhesive to the sheet when the element is moved to engage the sheet.

40 2. In a folding machine, the combination of a movable element operative to engage a sheet preliminary to a subsequent folding of the sheet, with a guide on the element, a nipple adjustable in the guide, and a source 45 of liquid adhesive communicating with the nipple, the nipple operating to apply a daub of the adhesive to the sheet when the element is moved to engage the sheet.

3. In a folding machine, the combination 50 of a movable blade operative to engage a sheet preliminary to a subsequent folding of the sheet, the blade having an elongated slot therein, with a guide on the blade extending over the slot therein, an elastic block slidable 55 in the guide, a nipple mounted in the block to extend through the slot in the blade, and a source of liquid adhesive communicating with the nipple, the nipple operating to apply a daub of the adhesive to the sheet when 60 the blade is moved to engage the sheet, and the sliding of the block in the guide operating to vary the position of the nipple to accommodate sheets and plies of different dimensions.

65 4. In a folding machine, the combination

of a movable element operative to engage a sheet preliminary to a subsequent folding of the sheet, with a nipple mounted in the movable element to contact with the sheet when the element is moved to engage the sheet, a support, a reservoir for liquid adhesive mounted in the support above the nipple, a flexible connection between the lower part of the reservoir and the nipple so that the nipple on contact with the sheet applies a daub of adhesive to the sheet when the element is moved to engage the sheet, and means for controlling the flow of adhesive from the reservoir to the nipple. 70

5. In a folding machine, the combination of a movable element operative to engage a sheet preliminary to a subsequent folding of the sheet, with a nipple mounted in the movable element to contact with the sheet when the element is moved to engage the sheet, a support, a reservoir for liquid adhesive vertically adjustable in the support above the nipple, a flexible connection between the lower part of the reservoir and the nipple so that the nipple on contact with the sheet applies a daub of adhesive to the sheet when the element is moved to engage the sheet, the vertical adjustment of the reservoir in the support operating to regulate the pressure of the adhesive flowing from the reservoir to the nipple, and means controlling the flow of the adhesive from the reservoir through the flexible connection. 75

6. In a folding machine, the combination of a movable element operative to engage a sheet preliminary to a subsequent folding of the sheet, with a source of liquid adhesive, and a nipple communicating with the source of adhesive and mounted to project in advance of the element to contact with the engaged sheet to apply a daub of adhesive thereto as the sheet is moved by the element in the subsequent folding of the sheet. 80

7. In a folding machine, the combination of a movable element operative to engage a sheet preliminary to a subsequent folding of the sheet, with a source of liquid adhesive, and a nipple communicating with the source of adhesive, an adjustable mounting for the nipple for positioning the discharge orifice of the nipple in advance of the element to contact with the engaged sheet to apply a daub of adhesive thereto as the sheet is moved by the element in the subsequent folding of the sheet, the adjustable mounting 100 being operative to position the nipple to provide an extended contact of the nipple with the sheet as the sheet is moved by the element in the subsequent folding of the sheet. 105

8. In a folding machine, the combination of a movable element operative to engage a sheet preliminary to a subsequent folding of the sheet, with a source of liquid adhesive, a nipple communicating with the source of adhesive, and adjustable means for mounting 110

the nipple on the element to project the nipple in advance of the element to contact with the engaged sheet to apply a daub of adhesive thereto as the sheet is moved by the element in the subsequent folding of the sheet, the adjustable means being operable to provide a variable contact of the nipple with the sheet.

9. In a folding machine, the combination of coacting folding rolls, one of the rolls having an annular groove, with a tucking blade operative to tuck a sheet between the rolls, and means for applying a daub of adhesive to the sheet in a position to register with the annular groove as the sheet travels between the rolls, the daub being applied to the inner face of one of the plies of the sheet so that when the two plies formed by the rolls are brought together the daub will be pressed between the two plies to form an adhesion therebetween.

10. In a folding machine, the combination with a source of liquid adhesive, of a nipple communicating with the source of liquid adhesive, and means for folding a sheet into plies, said means operating initially to move a ply of the sheet to contact with the nipple to receive therefrom a daub of adhesive, the subsequent folding of the sheet by said means pressing the ply with the daub against the adjacent ply in the completed fold.

In testimony whereof I affix my signature.
GEORGE ALEXANDER DUNAGIN.
